PRINTING MECHANISM

Benjamin H. Freedman, Asbury Park, N. J.

Application February 29, 1940, Serial No. 321,442

9 Claims. (Cl. 101—66)

This invention relates to printing mechanisms in general, and more especially to a printing mechanism for printing a marking, lettering, symbol or the like on a succession of mediums such as theatre tickets and the like.

Among the objects of the present invention, it is aimed to provide an improved printing mechanism for printing one of a series of markings, letterings, symbols or the like on a predetermined number of successive mediums such as theatre tickets and the like formed on a strip, and successively changing the marking, lettering, symbol or the like at the end of each run of a predetermined number so that a number of predetermined quantities of mediums such as theatre tickets or the like may be expeditiously printed in succession, each quantity of a predetermined number containing a different individual marking, lettering, symbol or the like of a series.

It is still another object of the present invention to provide an improved printing mechanism for printing a predetermined number of one of each of a succession of markings, letterings, symbols or the like on a predetermined number of mediums, such as theatre tickets and the like formed in a strip, with one marking, lettering, symbol or the like for each medium, ticket unit area or the like, which printing mechanism may readily be attached to a rotary press suitable for printing a strip of successive theatre tickets or the like.

These and other features, capabilities and advantages of the invention will appear from the subjoined detail description of one specific embodiment thereof illustrated in the accompanying drawings, in which

Figure 1 is a perspective of a ticket strip made according to the present invention;

Fig. 2 is a diagrammatic side elevational view of the printing mechanism attached to a rotary printing press or the like;

Fig. 3 is a fragmental side elevation partly in section of one of the main units of the improved mechanism;

Fig. 4 is a fragmental section on the line 4—4 of Fig. 3;

Fig. 5 is a section on the line 5—5 of Fig. 4;

Fig. 6 is a diagrammatic view of the wiring for the shift control;

Fig. 7 is a perspective detail of the guide for guiding the immediate strip into and out of printing position;

Fig. 8 is a fragmental section of the odd bearing with its associated printing wheels;

Fig. 9 is a side elevation of the odd bearing illustrated in Fig. 8;

Fig. 10 is an exploded perspective of one of the bearing plate units for supporting the printing wheels;

Fig. 11 is a section on the line 11—11 of Fig. 4; and

Fig. 12 is a fragmental detail particularly in section of one of the type wheels and its actuation.

According to the present invention, it is aimed to provide an improved machine for forming the symbols 1 on the ticket strip 2 illustrated in Fig. 1, one symbol 1 for each ticket unit area 3, the unit area 3 being about one inch in length and two inches in width. In other words, the width of the unit area 3 corresponds to the width of the strip 2, and the length of the strip 2 is a succession of lengths of unit areas 3. In the present instance, the strip 2 is provided with a longitudinally extending line 4, preferably a perforated line, and positioned off center to divide the strip into two lengths of stub areas 5 and 6, the narrow stub areas 5 reserved for the patrons and the broad stub areas 6 reserved for the accounting department of the theatre.

According to the present invention, the symbols 1 are not identical for all issues or series but purposely different or changed for successive issues, the number of different symbols 1 being indefinite, although to satisfy certain circumstances, fifty different symbols should ordinarily suffice. In view of the foregoing, the mechanism hereinafter to be described is equipped with symbol or type carrying wheels of which the wheel 7 illustrated in Fig. 4 is typical. According to the present invention, mechanism is provided whereby the change from one symbol to another will take place mechanically after having completed impressing a certain symbol on a predetermined number of ticket unit areas 3.

While the mechanism now to be described and illustrated is directed primarily for use with rotary presses, it will be obvious that mechanism made according to the principle of this invention can also readily be constructed for use with flat bed presses in which the chase or printing wheel is reciprocated into and out of impressing position.

In the present embodiment, see Fig. 2, the housing 8 of a rotary press of the type in which different printed matter is impressed on a strip of tickets at successive stations, is shown as having a supply roll of ticket material 9 mounted on the shaft 10 being fed through the housing where

it may pass through an initial station for receiving printed matter before passing on to the idler 11, from which the strip of ticket material 12 from the supply roll 9 then passes to and between the platen roller 13 and the printing drum 14. The printing drum 14 is shown as mounted on the shaft 15 which is drivingly connected with the driven shaft of the rotary press contained in the housing 8. From the drum 14, the strip then passes to and between the two idlers 16 and 17 to the next station determined by the roller platen 18 and printing drum 19 mounted on the shaft 20 which is likewise drivingly connected with the drive and the rotary press mounted in the housing 8. From the printing drum 19, the strip 12 then passes to and between the idlers 21 and 22 and from there back into engagement with subsequent printing stations in the rotary press of the housing 8. In the present instance, the type or symbols on the printing wheels 7 mounted in the drum 14 are inked by engagement with the inking roller 23 deriving its ink from the intermediate transfer roller 24 which in turn derives its ink from the reservoir roller 25 rotating in the reservoir 26, and similarly the type or symbols on the printing wheels 7 of the drum 19 are inked by the inking roller 27 deriving its ink from the transfer roller 28 in engagement with the main ink supply roller 29 rotatably mounted in the ink supply in the reservoir 30.

The drums 14 and 19 are positioned in the present instance to impress a symbol on alternate ticket unit areas 3 on the strip 1. In other words, if the drum 14 impresses the symbols 31, 32, 33 and so on, the drum 19 is timed to impress the alternate symbols 34, 35, and so on. In this way, the speed of the drums 14 and 19 may be reduced one-half. In conventional ticket printing machines today in use, it is not uncommon to print forty-five hundred unit ticket areas per minute. Since, as hereinafter to be described, each drum 14, 19 has forty-five type wheels 7 calling for forty-five impressions in each cycle or revolution of a drum 14 or 19, if only one drum were used to impress a symbol in each ticket unit as it passes through the rotary press, it would require one hundred revolutions per minute of such single drum. If two drums were used, and each carried forty-five printing wheels, the two drums would only need to revolve fifty times a minute. Obviously, it would not require invention to multiply the number of drums, further to reduce the speed of rotation. In other words, if three drums were used instead of two, each drum would print a symbol on one of three successive ticket unit areas, omitting the other two ticket unit areas for receiving impressions from the other two drums.

Since the drums 14 and 19 are substantially identical, it will suffice to illustrate one in detail. In Fig. 4, the drum 14 is shown as consisting of a disc portion 36 having a cylindrical portion 38 having in the present instance forty-five openings 39 to enable a portion of the type wheels 7 to extend therethrough. The inner face of the cylindrical portion 38 is recessed at 40 to receive the base portions 41 of the large bearing members 42, see Fig. 10. One of these main bearing members 42 is fixed to the cylindrical portion 38 by the screws 43 and 44 between each two successive printing wheels 7. The bearing members 42 have a radially extending plate portion 45 with a shoulder 46 at the bottom and a shoulder 47 at the top. The inner faces 48 and 49 of the shoulders 46 and 47 diverge from one another as

they approach the plate 45. In the plate portion 45 there is formed a bearing opening 50. In the space formed between the shoulders 47 and 46, there is slidably mounted the small bearing member 51, the faces 52 and 53 of which are inclined to cooperate with the inclined faces 48 and 49 respectively so that when the plate 51 is slidably positioned in the recess between the shoulders 46 and 47, it will be anchored against removal except by sliding it along the shoulders 46 and 47. In the bearing 51, there is also formed a bearing opening 54 which aligns with the bearing opening 50 in the large bearing plate 42.

In the process of assembly with an even number of type wheels 7, the main bearing plates 42 are first secured in place by the screws 43 and 44 to the inner face of the cylindrical wall 38 with a printing wheel 7 positioned between the opposing faces 55 of such bearing plates 42. The printing wheel as shown in Fig. 3, has a hub portion 56 and 57 extending from opposite faces thereof which are previously positioned in the bearing openings 50 of two plates 42 having the faces 55 opposing one another, or with a type wheel 7 disposed between the opposing faces 55 of two adjacent main bearing plates 42. Thereupon two small bearing plates 51 are positioned on the opposite hubs 56 and 57 of another type wheel 7 and these three elements as a unit are slidably mounted into place by sliding the small bearing plates 51 along in the recesses formed between the shoulders 46 and 47 of two adjacent main bearing plates 42 having the faces 58 of their shoulders 46 opposing one another. Thereupon, to anchor the slideable bearing members 51 with their associated printing wheel 7 in place, the closure member 59 is secured in place by the screws 60 extending through the closure member 59 and screw-threadedly connected to several of the main bearing plates 42. In the present instance, it has been found satisfactory to provide nine of such screws 60. The closure member 59 consists essentially of a disc member 61 and a cylindrical portion 62 abutting against the edge of the cylindrical portion 38 and overlapping the extended portions of the bases 41 of the main bearing plates 42.

The disc portion 36 of the drum portion 14 and the disc portion 61 of the closure member 59 are provided with openings 63 and 64 respectively, to receive the hollow shaft 65.

In the present instance the closure member 59 is provided with teeth 66 on its periphery for driving engagement with the drive of the rotary press formed in the housing 8. Adjacent to the teeth 66 and radially inward therefrom, there extends the cylindrical portion 62.

When an odd number of wheels such as used in the present instance is employed, then preferably before the bearing members 42 are secured in place, an odd shaped bearing member 67 is provided, see particularly Fig. 8 which has an elongated base portion 68 with a bearing opening 69 to receive the bearing collars 70 and 71 which in receive the hubs 57 and 56 of the type wheels 7. The outside hubs 56 and 57 of the type wheels 7 and 7 then have mounted thereon the small bearing plates 51 one on each hub 56, 57 and these two additional small bearing plates 51 together with the two type wheels 7, 7 and the odd shaped bearing member 67 are then slid into place between two previously fixed large bearing plates 42, see Fig. 3, and finally the base of the bearing plate 67 secured in place by the screws

72 extending through the cylindrical wall 38 of the drum portion 14.

Each of the type wheels 7, see Fig. 4, has a plurality of type 73 provided with faces for producing symbols, markings, letterings or the like. In the present instance it is desired to have each of this type 73 provided with a different symbol such as the symbols 1 shown in Fig. 1, each different from one another and fifty different ones formed on each wheel 7. Each wheel 7 preferably has the same fifty different symbols 73. Furthermore, the different symbols 73 on each wheel are arranged to succeed one another in the same order and for printing are positioned so that the same identical symbol will be printed during each cycle and for a succession of cycles, and when the symbols are changed, the symbols of all of the type wheels 7 are changed so that they will again expose another symbol but identical with one another.

As heretofore set forth, the drum 14 when associated with a companion drum 19 will be required to revolve fifty times in a minute in order to produce forty-five hundred characters in a minute if there are forty-five type wheels mounted on a drum consequently calling for forty-five impressions in a cycle. Furthermore, these type wheels 7 according to the present invention, are to be actuated to change the type exposed for impression only after a considerable run of any one predetermined symbol. In some instances it might be desirable to run only five thousand of a single symbol at a time, and other instances it might be desirable only to run one thousand of a single type at a time. There may be different reasons for having a greater or less number. As an instance, a theatre, possibly in New York, for a single session of one price possibly between 2 p. m. and 4 p. m., would average disposing of at least five thousand tickets a day. Such a theatre might therefore wish to have a ticket with a different symbol for each day but not tickets of different symbols for one and the same session of one and the same day, and therefore be satisfied with an allotment of tickets in which each five thousand tickets has a different symbol.

For actuating the type wheel 7 at the end of each run of a predetermined number, the mechanism now to be described has been provided. It consists essentially, see Figs. 3 to 6 inclusive, of nine bearings 74 secured to the enlarged portion 275 of the disc 61. Each of these bearings has pivoted thereto a bell crank 75 having an arm 76 provided with a pawl 77 connected to the end of the arm 76 by the spring 78. The end of the pawl 77 is provided with an extended plate 79 wide enough, see Fig. 3, so that it may engage five type wheels at a time. The edge of the plate 79, see Fig. 4, is positioned to engage in the spaces 80 formed between successive type 73. The bell cranks 75 are provided with the projections 81 co-operating with the compression springs 82 disposed between the projections 81 and the inner face of the enlargement 275 normally to press the arm 76 downward and the finger 79 into engagement with the recesses 80 of five type wheels 7. Each bell crank 75 is also provided with a substantially axially extending arm 82 having a roller 83 journaled at the outer end thereof to be engaged by the cam 84 on the link 85 pivoted at one end to the arm 86 fixed to the hollow shaft 65. The hollow shaft is provided with an opening 87 through which extends the lever 88 fixed on the shaft 89 extending through the hollow shaft 65 and journaled at one end adjacent the opening

87 and at the other end in the frame 90. The lever 88 is pivoted at one end to the link 91 which is pivoted at the other end to the free end of the lever 85. The lever 85 as clearly shown in Fig. 3, with its cam 84 extends radially outward of the rollers 83 so as to deflect them radially inward when a change is to take place, thereby in turn to actuate the pawls 77 to actuate the type wheels 7 a tooth space or as in the present instance, a type space distance.

10 The shaft 89 is actuated intermittently by the mechanism now to be described. The shaft 89 has fixed at one end thereof the lever 92 pivotally connected at one end to the link 93 of a toggle arrangement in association with the lever 94 pivoted at the other end of the link 93 and journaled on the bearing 95 fixed on the frame 90. The pivotal connection 96 between the link 93 and the lever 94 is connected by the link 97 to the armature 98 15 of the electro-magnet 99, the armature 98 being normally spring-pressed outwardly by the spring 100 when the electro-magnet is de-energized. The lever 92 is actuated and consequently the shaft 89 rotated to in turn actuate the lever 88 20 when the electro-magnet 99 is energized by the means now to be described. The electro-magnet 99, see Fig. 6, is electrically connected at one end by the conductor 101 with the contact 102 normally spaced apart from the contact 103 which 25 is connected by the conductor 104 to the conductor 105 of the main current supply. The other conductor 106 of the main current supply is connected by the conductor 107 to the other pole of the electro-magnet 99. The electro-magnet 30 35 99 is energized when the contacts 102 and 103 are engaged by the lever 111 which is controlled by the cam 112, the lever 111 having a spur 113 which engages the outer periphery of the cam disc 112, and when it drops into the recess 114, it closes the 40 switch formed by the contacts 102 and 103 in turn to energize the electro-magnet 99.

The cam disc 112 is fixed on the shaft 115, the speed of which in turn is controlled so that it will make a cycle for each predetermined number of 45 tickets constituting a run.

The speed of the shaft 115 is controlled by the mechanism now to be described. Assuming that the rate of printing is forty-five hundred tickets per minute and that with two drums, each drum prints twenty-two hundred and fifty tickets per minute, if each drum has forty-five type wheels it will require fifty revolutions per minute of each drum 14 and 19. Consequently, if the gear 116 is fixed to rotate with the drum 14, the speed of the shaft 115 can be controlled by operative connections associated with the gear 116. The drum 14 has fixed thereto the gear 116 which is in mesh with the gear 117 on the shaft 118. This shaft 118 has mounted thereon a worm 119 in mesh with the worm wheel 120 on the shaft 121 which shaft 121 may be associated with any suitable speed regulating device. The shaft 121 is of course the element which controls the in-going speed, that is, the speed going into the speed control mechanism, in the present instance, the Reeves variable speed transmission mounted in the housing 122. On the shaft 121, according to the variable speed transmission illustrated, there is fixed a sheave element 123 having an inclined face to cooperate with the sheave element 124 slidably mounted on the shaft 121. The inclined faces of the sheave elements 123 and 124 are connected by the belt 125 with the pulley consisting of the sheave elements 126 and 128 having inclined inner faces, the sheave element 126 fixed on the shaft

115 and cooperating with the sheave element 128 slidably mounted on the shaft 115. The shaft 115 in the present instance has fixed thereon the disc 112 shown in Fig. 6 to control the lever 111, in turn to control the contact 103 in its relation to the contact 104 to establish the circuit from the conductor 101 to the conductor 104.

As is conventional with and characteristic of the Reeves variable speed transmission, the speed translated from the shaft 121 to the shaft 115 will depend upon the positioning of the sheave elements 124 and 128 relative to the sheaves 123 and 126 respectively to correspond to the speed transmitted from the sheave elements 123 and 124 to the sheave elements 126 and 128 by the belt 125. To control the position of the sheave elements 124 and 128, the collars 129 and 130 to which the sheave elements 124 and 128 are fixed, are in turn fixed to rotate with the shafts 121 and 115 respectively but slideable on such shafts. The slideable position of these collars 129 and 130 is controlled by the lever 131 pivotally mounted on the pivot point 132 and operatively connected at 133 to the collar 129 and at 134 to the collar 130. The upper end of the lever is operatively connected to the collar 135 screw threadedly connected to the thread 136 on the shaft 137 journaled in the walls 138 and 139 of the housing 122. The outer end of the shaft 137 has mounted thereon the control wheel 140. The shaft 137 is further operatively connected to the pointer 141 which cooperates with the dial 142 calibrated to indicate in the present instance the number of tickets per revolution of the shaft 115 which will be printed by the forty-five printing wheels 7 in the arrangement illustrated. With a reduction arranged by the gears 116 and 117, worm 119 and worm wheel 120, whereby the shaft 121 will make a single revolution every time one hundred tickets are printed, then when the pointer 141 registers with the mark 143 on the dial 142, the intermediate or neutral speed will be transmitted to the shaft 115 so that the shaft 115 will likewise revolve once while one thousand tickets are printed. When the wheel 140 is turned so that the pointer 141 is positioned to the left of the mark 143, an increased speed will be transmitted to the shaft 115 so that during a single revolution of the shaft 115, a less number of tickets will be printed, and in turn when the pointer 141 is positioned to the right of the mark 143, a decreased speed will be transmitted to the shaft 115 and the shaft 115 will make a single revolution during the printing of more than one thousand tickets, depending upon the position of the pointer 141 on the dial 142 and in turn the setting of the sheave elements 124 and 128 relative to the sheave elements 123 and 126.

Now depending upon the setting of the pointer 141, the period when the lever 111 remains in its depressed contact-making position of the contacts 103 and 104 may be greater or less than the period required for the drum 14 to make one complete cycle and not more nor less than one complete cycle.

To maintain the cam lever 85 in its depressed position just for, and not more nor less than, a complete cycle, the mechanism now to be described is provided. On the frame 90 there is mounted a bearing in which there is journaled the shaft 144 on one end of which there is fixed the gear 145 in mesh with the gear 116. On the other end of the shaft 144 there is rotatably mounted the drum 150 having the cam recess 147 for receiving the cross piece 148 connecting the

plates 149 of the levers 94 with one another. The drum 150 also has a recess 151 therein to receive the clutching roller 152 having the stems 153 extending through the slots 154 to receive the springs 155 for connecting the stems 153 with the pins 156. The roller 152 is positioned in the recess 151 retracted by the springs 155 to connect the drum 150 in driving engagement with the shaft 144, being frictionally held by springs 155 between the inclined face 157 of the recess 151 and the shaft 144. The plates 149 have arcuate edges 158 for engaging the stems 153 against the tension of the springs 155 to maintain the roller 152 out of driving engagement with the shaft 144 when the electro-magnet 99 is deenergized and the armature 98 is in its distended position, that shown in Fig. 5. When, however, the electro-magnet 99 is energized, and the toggle elements 93, 94 are straightened out thereby to actuate the arm 92 in turn to rock the shaft 89 and thereby to rock the arm 85 into position for actuating the printing wheels 7, the plates 149 will clear the stems 153 and permit the springs 155 to press the roller 152 into driving engagement with the shaft 144. Thereupon, when the electro-magnet 99 is deenergized, the plates 149 will not immediately be free again to engage the stems 153 and retract the roller 152, but the cross piece 148 will engage the raised periphery of the drum 150 and remain so distended against the tension of the spring 100 until a complete cycle has been completed and the recess 147 permits the cross piece 148 again to drop into the same. So that not more than one type 73 engages the ticket strip 12 at one time as it passes into the printing position of the type wheel 7, preferably a guide 159, such as illustrated in Fig. 4 and more in detail in Fig. 7, is provided which consists essentially of a main plate portion 160 with flanges 161 and 162 turned over upon the plate 160, spaced therefrom but in alignment therewith, the plate portion 160 having an opening 163 to permit the rotatable platen 13 to engage one face of the strip 12 and hold it in printing engagement with the type 73 of the printing wheels 7. The edge portions 164 and 165 of the guide 159 are deflected outwardly away from the type 73 of the printing wheels 7 to deflect the strip 12 out of printing engagement with adjacent type 73 of the type wheels 7.

Preferably to check the printing wheels 7 against rotation and maintain them in printing position but yieldable to permit the feeding claws 79 to actuate the same, there are provided the check pawl blades 166 similarly engaging the printing wheels 7 between the successive type 73 and similarly engaging five printing wheels 7, and preferably the same five printing wheels as are engaged by their associated feeding claws 79. The blades 166 are formed at the ends of levers 167 pivotally mounted on the bearings 168 secured to the disc 36 adjacent to the hollow shaft 64, each with an extension 169 connected by a spring 170 with the inner face of the disc 36 to yieldably maintain the check pawl blades 166 in engagement with the printing wheels 7.

So that the check pawl blades 166 and the blades 79 do not mar the type face of the type 73, these blades 166 and 79 are preferably recessed to clear the type 73 but effectively to engage the ends of the recesses between the type 73, as shown in Fig. 12, the recesses 180 being sufficient to clear the edge of the type 73 when riding on the peripheral portions 181 of the type wheels 7. The blades

166 are similarly provided with recesses (not shown) such as the recesses 180.

Preferably also, so that the ink is effectively cleaned from the type 73 before each successive impression, and particularly before effecting a change of type, an ink removing device is provided immediately after the printing position, see Fig. 3, so that the roller 172 preferably composed of a suitable buffering material such as rubber, felt or the like, is spring-pressed into engagement with the type 73 of the drum 14. The roller 172 is also spring-pressed into engagement with the steel roller 173 in engagement with which there is provided the scraper 174 for removing and depositing the ink received by the steel roller 173 into the receptacle 175. Preferably the gear 176 on the shaft of the roller 172 is drivingly connected to the teeth 68 of the drum 14 by the intermediate gear 177 so that the buffering roller 172 may rotate in the opposite direction to that of the drum 14. Preferably also the steel roller 173 is provided with a gear 178 driven from gear 176 through the intermediate gear 179 so that it likewise will rotate in a direction opposite to that of the buffering roller 172.

It is obvious that various changes and modifications may be made to the details of construction without departing from the general spirit of the invention as set forth in the appended claims.

What I claim is:

1. The combination of a rotatable type-carrying drum having a disc and a cylindrical wall extending from said disc with a plurality of axially extending slots in said wall terminating in the outer free edge of said wall, a plurality of bearings secured to the inner face of said cylindrical wall, a plurality of type wheels journaled in said bearings radially mounted in said drums with their axes transverse to the axis of said drum, one slot for each type wheel to enable a type of each type wheel to extend through said slot to cooperate with a strip intermediate the type and the platen to impress a marking on the strip and facilitating the positioning of said type wheels, a closure for the drum having a cylindrical wall in alignment with the cylindrical wall of the drum and connected thereto to close the free ends of said slots, said closure having gear teeth on its periphery for cooperation with actuating means to rotate said drum.

2. The combination of a printing support, a drum, means for actuating said drum to rotate with its cylindrical face moving with and in the direction of the path of movement of a strip to receive the impressions, a plurality of type wheels having outwardly extending hubs, fixed and slidably bearing plates for supporting said type wheels radially in said drum with their axes transverse to the axis of the drum, said fixed bearing plates arranged in pairs and secured to the inner cylindrical face of said drum and having recesses in the opposing faces of each pair, a pair of slidably bearing plates slidably into said recesses between a pair of fixed bearing plates, the hubs of one type wheel journaled in a pair of said slidably bearing plates and disposed between a pair, the adjacent outer faces of adjacent pairs of fixed bearing plates being spaced apart to receive a type wheel journaled in the opposing outer fixed bearing plates, and a closure including a disc for anchoring said slidably bearing plates in place, each type wheel having a plurality of different type on its periphery, there being openings in the cylindrical wall of said drum, one opening for

each type wheel to enable the type of each type wheel to extend through an opening to cooperate with the strip intermediate the type and the support to impress a marking on the strip.

3. The combination of a printing support, a drum including a disc having a cylindrical wall extending therefrom with a plurality of openings in said cylindrical wall extending axially and terminating at the free edge of said cylindrical wall, 10 a plurality of type wheels having outwardly extending hubs, fixed and slidably bearing plates for supporting said type wheels radially in said drum with their axes transverse to the axis of the drum, said fixed bearing plates arranged in pairs 15 and secured to the inner face of said cylindrical wall with one fixed bearing plate between each two successive openings in said cylindrical wall, there being recesses in the opposing faces of each pair of fixed bearing plates, a pair of slidably bearing plates slidably into said recesses between a pair of fixed bearing plates, the hubs of one type wheel journaled in a pair of said slidably bearing plates and disposed between a pair, the adjacent outer faces of adjacent pairs of fixed bearing plates being spaced apart to receive a type wheel therebetween with the hubs of such type wheel journaled in the opposing outer fixed bearing plates, and a closure including a disc for anchoring said slidably bearing plates in place.

30 4. The combination of a printing support, a drum, means for actuating said drum to rotate with its cylindrical face moving with and in the direction of the path of movement of a strip to receive impressions, a plurality of type wheels 35 radially mounted in said drum with their axes transverse to the axis of the drum, each type wheel having a plurality of different type on its periphery, there being openings in the cylindrical wall of said drum, one opening for each type wheel to enable a type of each type wheel to extend through an opening to cooperate with the strip intermediate the type and the support to impress a marking on the strip, a mechanism for actuating said printing wheels intermittently 40 while the drum is rotating to enable a change of type to be made without arresting either the feed of the strip or the rotation of the drum, said mechanism including a plurality of pivotally mounted spring pressed claws, each claw engaging a number of successive type wheels at their periphery between successive type, a plurality of check pawls corresponding in number to said claws and each associated with a claw and having a blade cooperating with the peripheries between 45 successive type of the same type wheels engaged by its associated claw, and means for intermittently actuating said claws.

5. The combination of a cylindrical type carrying drum, a plurality of type wheels having outwardly extending hubs, fixed and slidably bearing plates for supporting said type wheels radially in said drum with their axes transverse to the axis of the drum, said fixed bearing plates arranged in pairs and secured to the inner cylindrical face 60 of said drum and having recesses in the opposing outer faces of each pair of fixed bearing plates, a pair of slidably bearing plates slidably into said recesses between a pair of fixed bearing plates, the hubs of certain of said type wheels journaled in a pair of said slidably bearing plates, the adjacent inner faces of each pair of fixed bearing plates being spaced apart to receive a type wheel therebetween with the hubs of such type wheel journaled in the opposing inner faces of such pair 65 of fixed bearing plates, and a closure including a 70 75

disc for anchoring said slidable bearing plates in place, each type wheel having a plurality of different type on its periphery, there being openings in the cylindrical wall of said drum, one opening for each type wheel to enable the type of each type wheel to extend through an opening to impress a marking on a strip.

6. The combination of a rotatable type carrying drum having a disc and a cylindrical wall extending from said disc with a plurality of axially extending slots in said cylindrical wall terminating in the outer free edge of said wall, one set of bearings secured to the inner face of said cylindrical wall, one set of type wheels journaled in said bearings radially mounted in said drum with their axes transverse to the axis of said drum, a second set of bearings slidably connected to said first set of bearings, a second set of type wheels journaled in said second set of bearings and also radially mounted in said drum with their axes transverse to the axis of said drum, one of said slots for each of said type wheels to enable a type of each of said type wheels to extend through its slot to impress a marking on a strip, and a closure for the drum connected to said cylindrical wall to close the free ends of said slots and engaging the outer edges of said slidable brackets to position the same.

7. The combination of a rotatable type carrying drum having a disc and a cylindrical wall extending from said disc with a plurality of axially extending slots in said cylindrical wall terminating in the outer free edge of said wall, one set of bearings secured to the inner face of said cylindrical wall, one set of type wheels journaled in said bearings radially mounted in said drum with their axes transverse to the axis of said drum, a second set of bearings slidably connected to said first set of bearings, a second set of type wheels journaled in said second set of bearings and also radially mounted in said drum with their axes transverse to the axis of said drum, one of said slots for each of said type wheels to enable a type of each of said type wheels to extend through its slot to impress a marking on a strip, and a closure for the drum connected to said cylindrical wall to close the free ends of said

slots and engaging the outer edges of said slidable brackets to position the same, said closure having gear teeth on its periphery for cooperation with said actuating means to rotate said drum.

8. The combination of a cylindrical type carrying drum, a plurality of type wheels having outwardly extending hubs, fixed and slidable bearing plates for supporting said type wheels radially in said drum with their axes transverse to the axis of the drum, said fixed bearing plates arranged in pairs and secured to the inner cylindrical face of said drum and having recesses in the opposing outer faces of each pair of fixed bearing plates, a pair of slidable bearing plates slidable into said recesses between a pair of fixed bearing plates, the hubs of certain of said type wheels journaled in a pair of said slidable bearing plates, the adjacent inner faces of each pair of fixed bearing plates being spaced apart to receive a type wheel therebetween with the hubs of such type wheel journaled in the opposing inner faces of such pair of fixed bearing plates, each type wheel having a plurality of different type on its periphery, there being openings in the cylindrical wall of said drum, one opening for each type wheel to enable the type of each type wheel to extend through an opening to impress a marking on a strip.

9. The combination of a rotatable type carrying drum having a disc and a cylindrical wall extending from said disc with a plurality of axially extending slots in said cylindrical wall terminating in the outer free edge of said wall, one set of bearings secured to the inner face of said cylindrical wall, one set of type wheels journaled in said bearings radially mounted in said drum with their axes transverse to the axis of said drum, a second set of bearings slidably connected to said first set of bearings, and a second set of type wheels journaled in said second set of bearings and also radially mounted in said drum with their axes transverse to the axis of said drum, one of said slots for each of said type wheels to enable a type of each of said type wheels to extend through its slot to impress a marking on a strip.

BENJAMIN H. FREEDMAN.
